UNITED STATES PATENT OFFICE.

STEPHAN SZÜCS, OF BELOIT, WISCONSIN.

HEEL FOR BOOTS AND SHOES.

1,233,725.

Specification of Letters Patent. Patented July 17, 1917.

Application filed March 2, 1917. Serial No. 151,876.

To all whom it may concern:

Be it known that I, STEPHAN SZÜCS, a subject of the King of Hungary, resident of Beloit, county of Rock, and State of Wisconsin, have invented certain new and useful Improvements in Heels for Boots and Shoes, of which the following is a specification.

This invention relates to improvements in heels for boots and shoes, and has as its principal object the provision of a heel which may be removably engaged with the sole of the shoe, thus permitting a new heel to replace one which has been worn or becomes otherwise unfit for use.

A further object is to provide such removable heels with means whereby they may be adjusted so as to correctly agree with the formation of the rear part of the shoe.

These and other like objects are attained by the novel design, construction and combination of parts hereafter described and shown in the accompanying drawing, forming a material part of this specification, and in which:

Figure 1 is a side elevational and sectional view of the shoe showing the heel attached.

Fig. 2 is a fragmental bottom plan view of the same.

Fig. 3 is a plan view of the heel.

Fig. 4 is a side elevation, partially in section, of one of the holding means, and

Fig. 5 is a like view of the other holding means.

The invention comprises a heel 10 having a plurality of cylindrical recesses 11, formed in its lower side, the same terminating in elongated slots 12 which lead to oppositely disposed recesses 13 formed from the other side of the heel.

Thimble nuts having stems 15 are inserted through appropriate openings formed in the sole of the shoe until the enlarged heads 16 rest firmly against it, the stems having screw-threads 17 formed centrally therein and adapted to be engaged by the screws 20 having heads 21 seated on the shoulders 22 formed at the bottom of the openings 11, the stems 15 extending inward from the opposite side in the recesses 13 which are made larger in diameter than the stems so as to

allow for a moderate adjustment whereby the heel may be caused to register with the rear of the shoe by slackening the screws 55 20 and moving the heel into an adjusted position, whereupon the screws are tightened in the threads 17, firmly drawing the parts against the sole.

A thin covering 24, formed in the manner 60 of an insole, is put within the shoe so as to cover the heads 16 of the thimble nuts.

From the foregoing, it will be clearly understood that whenever a heel needs renewing, it is only necessary to withdraw the 65 screws 20, remove the heel and replace the same with another, and it will be evident that the heel may be adjusted to its correct position, either originally or should the same become moved from any cause.

Having thus described my invention, what I claim as new, and desire to secure by Letters Patent, is—

1. The combination with a shoe, of a heel engageable therewith, said heel having a 75 plurality of recesses extending inward from both sides thereof, and a slot communicating therebetween, of internally threaded thimbles extending into the recesses formed in one side of said heel from the sole and 80 having heads engageable on the inner side thereof, screws operable in the opposite openings in said heel engageable with said thimbles, and means for covering the heads of said thimbles interiorly of said shoe. 85

2. The combination with a shoe, of a heel removably engageable therewith, said heel having a plurality of circular openings extending inward from the top and bottom thereof, and communicating elongated slots 90 therebetween, of internally threaded studs engageable in the sole of said shoe having heads resting upon the inner side thereof, said studs being loosely contained in the recesses on one side of said heel plate, screws 95 engageable in said stud, a head in said screws resting upon a shoulder formed in the oppositely formed recess, and means for covering the heads of said studs in the interior of the shoe. 100

In testimony whereof I have affixed my signature.

STEPHAN SZÜCS.
